United States Patent [19]

Cohen et al.

[11] Patent Number: Des. 383,036

[45] Date of Patent: Sep. 2, 1997

[54] FILTER CAKE HOLDER

[75] Inventors: Bernard Cohen, Berkeley Lake; Lee Kirby Jameson, Roswell, both of Ga.[73] Assignee: Kimberly-Clark Corporation, Neenah, Wis.

[] Term: 14 Years

[21] Appl. No.: 46,497

[22] Filed: Nov. 16, 1995

[51] LOC (6) Cl. 07-01

[52] U.S. Cl. D7/400

[58] Field of Search D7/400, 387, 300, D7/412, 305, 397, 310, 507, 391, 509, 504, 510, 392.2, 511, 536; D10/46.2; D9/434; 220/713, 709, 705, 729, 730; 97/295, 306, 300, 286, 304; 215/293; D23/209
